BOOK END

Bert M. Morris, Los Angeles, Calif.

Application April 19, 1951, Serial No. 14,895

Term of patent 14 years

(Cl. D33—1)

To all whom it may concern:

Be it known that I, Bert M. Morris, a citizen of the United States, residing in the city of Los Angeles, in the county of Los Angeles, and State of California, have invented a new, original, and ornamental Design for a Book End, of which the following is a specification, reference being had to the accompanying drawings, forming part thereof.

Fig. 1 is a perspective view of a book end, showing my new design.

Fig. 2 is a front view in elevation.

Fig. 3 is a side view in elevation.

Fig. 4 is a top plan view.

Figs. 5 and 6 are sectional views on lines of the corresponding numbers in Fig. 2 looking in the direction of the arrows.

I claim:

The ornamental design for a book end, substantially as shown and described.

BERT M. MORRIS.
